AXLE ASSEMBLIES

Walther F. Scheel, Detroit, Mich., assignor to Rockwell-
Standard Corporation, a corporation of Pennsylvania
Filed Sept. 6, 1957, Ser. No. 682,531
11 Claims. (Cl. 280—81.5)

This invention relates to improvements in vehicle axles and suspensions and has particular reference to dirigible tandem axle assemblies.

It is the primary object of this invention to provide a dirigible tandem axle assembly embodying the features of stability, over-all ruggedness and a spring suspension which distributes the load equally on both axles that have been heretofore built only into non-dirigible tandem axle assemblies while providing a short turning radius and ease of steering through a steering control linkage in which front wheel steering is proportioned by a pitman arm between axles and by steering cross tube arms and cross tubes on each axle in such a manner that the dirigible wheels turn about a common center located substantially on a lateral extension of the laterally extending center line of the rear tandem drive axle assembly.

A further object of the present invention is to provide a dirigible tandem axle assembly embodying either driving or non-driving axles and which provides free pivoting and vertical displacement of the axles to conform to ground irregularities while assuring maximum stability of the assembly, ease of steering and a small vehicle turning radius by construction and arrangement of the steering linkage in such a manner that it does not interfere with the turning movement of the dirigible wheels.

More specifically it is an object of this invention to provide a dirigible tandem axle assembly embodying a pair of closely spaced torque rod stabilized dirigible drive gear non-driving axles having leaf springs extending therebetween which centrally support a transversely extending cross tube providing a frame support with respect to which the axles are freely articulated and fully stabilized whereby the steering linkage and suspension are substantially relieved by the torque rods of vibration and torque induced stresses.

Another object is to provide a low center of gravity in the spring suspension for dirigible tandem axle assemblies.

A further object of this invention is to provide an improved dirigible tandem axle assembly of the type described of such improved construction and arrangement that the axis of the cross tube journalled on the leaf spring suspension is located in a horizontal plane at least as low as the plane defined by the axle axes or below such plane.

A further object is to provide a dirigible tandem axle assembly embodying completely stabilized axles each positioned by a parallelogram system of torque rods and a sway bar linkage for keeping the tandem axle assembly and chassis centerlines substantially in perpendicular relationship at all times.

Further objects of the present invention will become apparent from the following description, when considered in connection with the accompanying drawings and the appended claims.

In the drawings which illustrate several simple and practical embodiments of the invention:

FIGURE 1 is a side view of an eight wheeled vehicle embodying a rear tandem drive axle assembly and a front dirigible tandem axle assembly in accordance with the present invention;

FIGURE 2 is a fragmentary top plan view of a dirigible tandem axle assembly having non-driving dirigible axles constituting a first embodiment of the present invention;

2

FIGURE 3 is a fragmentary side view of the assembly of FIGURE 2;

FIGURE 3A is a fragmentary view showing the forward extension of the steering mechanism of the assembly as illustrated in FIGURE 3;

FIGURE 4 is a fragmentary sectional view taken substantially along line 4—4 of FIGURE 2 showing trunnion tube mounting seat spring and pitman arm details;

FIGURE 5 is a fragmentary rear end view partially in section showing the rear axle of the tandem axle assembly shown in FIGURES 2 and 3 and taken substantially on line 5—5 of FIGURE 2;

FIGURE 5A is a fragmentary sectional view taken substantially along the line 5A—5A of FIGURE 5;

FIGURE 6 is a fragmentary top plan view, similar to FIGURE 2, of a dirigible tandem axle assembly having live steering axles and constituting a second embodiment of the present invention;

FIGURE 7 is a fragmentary side elevational view, partially in section, of the assembly of FIGURE 6;

FIGURE 8 is a fragmentary rear end view, partially in section, showing the rear live steering axle of the assembly shown in FIGURES 6 and 7;

FIGURE 9 is a fragmentary side elevational view, similar to FIGURES 3 and 7, of a further dirigible tandem drive axle assembly constituting a third embodiment of the present invention;

FIGURE 9A is a fragmentary view of forward extension of the steering linkage of the assembly of FIGURE 9;

FIGURE 9B is a fragmentary rear end view of the assembly of FIGURE 9;

FIGURE 10 is a top plan view of a dirigible tandem axle assembly having live steering axles and equipped with lateral axle stabilizing means constituting a fourth embodiment of the present invention;

FIGURE 11 is a fragmentary transverse sectional view of FIGURE 10 taken substantially along the line 11—11 of FIGURE 10 and showing the lateral axle stabilizing means;

FIGURE 12 is a fragmentary plan view of a tandem axle assembly embodying another axle lateral stabilizing means and constituting a fifth embodiment of the present invention;

FIGURE 13 is a fragmentary transverse sectional view of the axle and lateral stabilizing means of FIGURE 12, taken substantially along the line 13—13 of FIGURE 12; and

FIGURE 14 is a fragmentary rear end view of the assembly of FIGURE 12.

With reference to the drawings, FIGURE 1 illustrates an automotive vehicle 10 embodying a rigid frame 12 having rigidly interconnected longitudinally extending parallel side frame members 14 supported at the rear by a non-dirigible tandem drive axle assembly 16 and at the front by dirigible tandem axle assembly 18 which may embody either driving or dead (non-driving) axles as will become apparent presently. Vehicle 10 is equipped with engine 20, a cab 22 located over the engine 20, and a drive train (partially described in the following) from engine 20 to tandem drive axle assembly 16 and, if assembly 18 is also equipped with drive axles, to assembly 18 through a transfer case in accordance with conventional practice. Both tandem axle assemblies 16 and 18 have floating spring suspensions 24 and leaf springs of which are centrally pivoted on a transversely extending trunnion 26 which is mounted by bracket assemblies 28 beneath the frame 12. Wheels 30 and 32 are mounted on dirigible axles 38 and 40 respectively of dirigible tandem axle assembly 18 and wheels 34 and 36 are mounted on drive axles 42 and 44 respectively of rear tandem drive axle assembly 16. Use of floating type

spring suspension 24 at both rear and front tandem axle assemblies 16 and 18 maintains frame lift at the tandem axle assembly at one-half obstruction height as one wheel (steering wheels 30 or 32 at the front tandem axle assembly 18 and drive wheels 34 or 36 at the rear tandem axle assembly 16) of the tandem axle assemblies passes over an obstruction. Frame twist at the front of vehicle 10 is half or less than half the frame twist which is encountered at the front of single front axle vehicles for an obstruction of any given height.

Referring to FIGURES 2 through 5, a preferred embodiment of the invention is therein disclosed embodied in a dirigible tandem axle assembly 18 having closely spaced dead (non-driving) axles 38 and 40 the axle beam of each having "T" section center portions 46 extending between axle mounted spring end brackets 48. The "T" section of the axle beams continues from center portions 46 through enlarged "I" sections 50 (see FIGURE 2), at which spring end brackets 48 are fixed to the axle by bolts 52, and then gradually changes to an oval section 54 (see FIGURE 5) adjacent the axle king pin boss 56. Referring again to FIGURE 2, spaced parallel longitudinally extending leaf springs 58, only one of which is shown, extend between and rest at their opposite ends on the axles 38 and 40, their ends 60 each resting on the convex surface 62 of a pillow block 64 disposed within a through opening 66 in bracket 48. The stirrup like openings 66 in brackets 48 restrict rebound of the ends of springs 58 and assist in maintaining axles 38 and 40 in lateral alignment with respect to the frame 12, leaf springs 58 acting as alignment members. A clearance is provided in brackets 48 between side abutting surfaces 68 and the side edges of the spring ends 60 to allow limited axle tracking self-alignment and free articulation of the axles, within limits, to accommodate ground surface irregularities.

As is most clearly illustrated in FIGURES 2, 3, and 4, the front end of vehicle frame 12 is pivotally suspended between axles 38 and 40 at the center of leaf springs 58, spring seats 70 which are clamped to the center of springs 58 being mounted for oscillating rocking movement on the ends of the transversely extending trunnion tube 72 which is fixed between upwardly extending frame support assemblies 28 that are fixed to frame 12. A machined channel 74 (FIGURE 4) in each spring seat 70 snugly holds at least the lowest main leaf 76 of the leaf spring 58. Leaf springs 58 are clamped to spring seats 70 by U bolt assemblies 78. With this construction any axle aligning function of each spring 58 is effected solely through the main leaf or leaves 76 which are held by seat 70. Leaf springs 58, due to their central pivotal connection to frame 12, divide the front axle load of the vehicle equally between axles 38 and 40 and provide resiliency which adds to the shock-reducing action in the above described balanced spring arrangement to give a cradle support for the front end of frame 12.

Referring to FIGURES 2 and 3, axles 38 and 40 are each connected to frame bracket assemblies 28 by upper and lower parallel longitudinally extending torque rods 80 provided at each side of the longitudinal centerline of tandem axle assembly 18. Upper torque rods 80 are universally equipped at each end with rubber bushed ball end stud assemblies 82 of the type disclosed in detail in copending application Serial No. 623,858 filed December 6, 1956 by James M. Prange for Universal Joint, and having a common assignee with the instant case, the studs of assemblies 82 at one end of torque rods 80 being received in openings 84 (FIGURE 4) of frame bracket assemblies 28 and the studs of assemblies 82 at the other ends of torque rods 80 being received through an upwardly extended boss 86 (FIGURE 5) of axle brackets 48. Lower torque rods 80 are universally mounted at one end in openings 88 (FIGURE 4) of frame bracket assemblies 28 and at the other ends on the downwardly extended arms 90 (FIGURES 4 and 5)

of axle brackets 48 by rubber bushed ball pin assemblies 82. This arrangement provides dirigible tandem axle assembly 18 with a parallelogram system of torque rods 80 connecting each of the axles 38 and 40 to the frame 12 through brackets 28. Torque rods 80, which act like a pantograph, transmit all braking and any other torsional forces that may be imparted to the axles 38 and 40 to vehicle frame 12 and restrain axles 38 and 40 from rotation about their axes while permitting vertical displacement and tipping of each axle to accommodate ground surface irregularities.

Referring to FIGURE 5 in which the axle outer end construction is shown in detail, at each end of axles 38 and 40 a king pin 92 having a centrally tapered shank 94 is tightly seated at its tapered central region in tapered opening 96 of the steering knuckle boss 56 and pivotally mounts a steering knuckle 98. Steering knuckle 98 is formed with an upper boss 100 apertured at 102 and journaled by bushings 104 on upper cylindrical end portion 106 of the king pin shank 94 and with a lower boss 108 apertured at 110 and journaled by bushing 112 on the lower cylindrical end portion 114 of king pin shank 94. Each king pin 92 is tightly seated in the steering knuckle boss opening 96 by a nut 116 abutting the inner one of the two concentric bushings 104 and threaded on the threaded end portion 118 at the top of and integral with the king pin 92. The center section 120 of steering knuckle 98 between bosses 100 and 108 is formed with a cylindrical shoulder 122 from the outer face of which an integral wheel spindle projects. In this embodiment king pins 92 are so inclined, as for example at an angle of 8° from the vertical toward the center of the vehicle frame, as to reduce tire overhang without encountering an undesirable amount of axle center lift when steering knuckles 98 are turned about the axis of king pin 92. Wheel spindle 124 is formed with threads 126 at its outer end to receive a wheel adjusting nut 128. Spaced opposed tapered roller thrust bearings 130 and 132 are provided on spindle 124 to journal wheel hub 134 and brake drum 136 which is coaxially fixed to hub 134 by bolts 137. The wheels 30 and 32 are mounted on hubs 134 of axles 38 and 40 respectively by bolts 137a in the conventional manner. A brake backing plate 138, which supports a cam actuated internally expandable brake mechanism assembly 140 concentrically within the drum 136, is fixed to steering knuckle shoulder 122 by rivets 142 circumferentially spaced about the axis of spindle 124.

50 A set screw and lock nut assembly 144 is mounted in threaded opening 146 of each steering knuckle center section 120 for adjustment to limit wheel turning angle by abutment with boss 148 on the axle boss 56.

As is most clearly shown in FIGURES 2 and 5 and 5A, 55 upper steering arms 150 and 152 of axles 38 and 40 respectively, which are connected to the steering linkage as will be explained presently, are received and fixed in tapered apertures 153 formed in the end region of upper bosses 100 of the steering knuckles 98 associated with 60 the wheels of assembly 18 at the left side of the vehicle 10. Lower steering arms 154 and 155, which form part of the interconnections between the wheels of the opposite ends of axles 38 and 40 respectively, are fastened to the lower bosses 108 of each of the steering knuckles 98 of the assembly 18. Steering arms 150, 152, 154 and 155 are rigidly attached to the respective bosses 100 and 108 by a connection formed by the coaction of their tapered end regions with the similarly tapered openings through bosses 100 and 108, keys 158 preventing 65 relative rotation therebetween, and nuts 160 received and tightened on the threaded end region 162 of each arm to hold the parts in rigid assembly.

Upper steering arm 150 extends axially inwardly from the upper steering knuckle boss 100 of the left wheel 75 30 of axle 38 as is shown in FIGURES 2 and 5 and

has a ball stud assembly 168 fixed thereto at its inner end. Stud assembly 168 projects upward from arm 150 and forms part of a universal joint connection 169 with the forward end 170 of adjustable length front drag link rod 172. End 170 is threaded at 173 into the internally threaded hollow end of rod 172, and fixed relative thereto by a lock nut 174. Upper steering arm 152 on rear wheel 32 extends axially inwardly and upwardly from the upper steering knuckle boss 100 of the left wheel 32 of axle 40 and has a ball stud assembly 168 fixed to the end thereof which projects downwardly to form part of a universal joint connection 175 with the rear end of a similarly adjustable length rear drag link rod 176. A downwardly depending pitman arm 178 (FIGURES 2, 3, 4, and 5) is axially fixed on and pivotally mounted on a stub shaft 180 carried by a bracket 182 which is bolted at 184 to the left side of member 14 of frame 12. The rear end of front drag link 172 is universally connected at 186 by a ball stud assembly 168 with the lower end of the inside of pitman arm 178. The forward adjustable length end of rear drag link rod 176 is connected by a universal joint 188 embodying a ball stud assembly 168 to pitman arm 178 at a position higher and closer to the pivot axis of pitman arm 178 than the universal joint connection 186 of front drag link 172 and is located on the outside of pitman arm 178 as is most clearly shown in FIGURE 4.

Referring to FIGURE 2, drag link 172 is bent so that it extends forwardly above spring 58 from universal joint connection 186 from the inside of pitman arm 178 and then angularly outwardly to universal joint connection 169 at a position in which it cannot interfere with the turning of the left front wheel. Greater drag link clearance for left front wheel 30 is provided than for left rear wheel 32 with drag link 176, which extends substantially straight back from universal joint connection 188 from the outside pitman arm 178 to universal joint connection 175, because for a given turning radius of the vehicle, the front wheels 30 must turn in greater amount than the rear wheels 32 of assembly 18. This arrangement assures a minimum turning radius while maintaining the simplicity of the steering linkage and permitting use of a linkage which will assure tracking of all four wheels of assembly 18 substantially about a common center during turning.

In the preferred embodiment of FIGURES 2-5 there is a difference in the distance between the pivotal center of steering knuckle 98 of the front axle 38 at the left front wheel 30 and the universal joint connection 169 and the corresponding distance between the pivotal center of knuckle 98 of rear axle 40 and the universal joint connection 175. This difference in distance and the relative angular dispositions of universal connections 169 and 175 as related to the respective pivotal centers of steering knuckles 98 helps to insure that wheels 30 and 32 on the left side of front tandem axle assembly 18 track substantially about the same center at any particular adjusted position through the entire steering range. Another factor which helps insure the proper tracking and correct wheel turning angles for left wheels 30 and 32 is the different spacings of the universal joint connections 186 and 188 from the pivot axis of pitman arm 178. Because of these linkage factors, any given movement of pitman arm 178 has a greater turning effect upon front left wheel 30 than upon left wheel 32.

A main steering drag link rod 200 is connected to pitman arm 178 by a universal joint connection 202 embodying a ball stud assembly 168 fixed to pitman arm 178 at the inside of the arm 178. Rod 200 is of adjustable length and its forward end is universally connected by a universal joint connection 203 (FIGURE 3A) embodying a ball stud assembly 168 to a forward steering mechanism pitman arm 204. Pitman arm 204 is pivotally mounted at 206 upon a bracket 208 which is fastened to the forward left side member 14 of frame

12. A drag link rod 210, which is connected by a universal joint connection 211, embodying a ball stud assembly 168, to pitman arm 204, extends forwardly and is connected either directly to the output pitman arm of a conventional steering wheel controlled worm gear mechanism (not shown) or to the output of power steering means (not shown).

Referring to FIGURES 2, 5 and 5A, lower steering arms 154 and 155 extend toward the vehicle rear and to a lesser extent axially inward from the respective lower steering knuckle boss 108 to a ball stud end assembly 212. Ball stud end assemblies 212, which may be shown in application Serial No. 343,163, filed March 18, 1953, by Leo A. Bixby for Joint, matured into United States Letters Patent No. 2,807,486 issued September 24, 1957, depend from arms 154 and 155 and provide a universal joint connection between lower steering arms 154 and 155 and an adjustable length steering cross tubes 214 and 216. Cross tubes 214 and 216 are similarly connected at their opposite ends to the steering knuckles of the wheels at the opposite ends of axles 38 and 40 respectively. The relative angular dispositions of ball stud end assemblies 212 at the ends of lower steering arms 154 and 155 are related in the same manner to the pivotal centers of the steering knuckles 98 to provide properly related wheel turning with a steering axle. This insures that wheels 30 at opposite ends of axle 38 and that wheels 32 at opposite ends of axle 40, as tied together by cross tubes 214 and 216, turn to track circles at any particular instance about substantially the same center point.

FIGURES 6 through 8 disclose a dirigible tandem drive axle assembly 218 constituting a second embodiment of the present invention. Assembly 218 comprises a pair of closely spaced dirigible drive axles 220 and 222. Axles 220 and 222 are each provided with top mounted carriers 240 with through drive bevel gear input assemblies 242. The axle housing 244 of both axle 220 and 222 has a short axle shaft housing extension 246 to the left side of the differential receiving section 247 and a long axle shaft housing extension 248 to the right side of section 247.

Leaf spring assemblies 249 of tandem axle assembly 218 are pivotally mounted on a trunnion tube 250 by spring seats 251 in the same manner as in the embodiment of FIGURES 2 to 5. Leaf spring assemblies 249 are however, as is most clearly shown in FIGURE 7, elliptical inverted leaf springs the ends of which rest on the upwardly facing convex surface 252 of respective pillow blocks 253 (FIGURES 7 and 8) which are suspended beneath the axles 220 and 222 by spring hanger brackets 254 and 255. Brackets 254 and 255, although similar in most respects, differ in that the torque rod mounting arms 256 which extend down from the inner side of each bracket 254 and 255, are located to the rear at the rear axle 222 and forwardly at the front axle 220 (FIGURE 7). The brackets 254' and 255' supporting the right leaf spring on the opposite ends of axles 220 and 222 are identical to brackets 255 and 254 respectively, being reversed in the mounted positions so that bosses 256 of all of the brackets 254 and 255 are adjacent the longitudinal centerline of assembly 218. Stirrup like openings 257 (FIGURE 8) in brackets 254 and 255 restrict rebound of the ends of springs 249 and help maintain axle alignment of assembly 218 with respect to frame 12 by side contact of stirrup plates 258 with the inner end edges of springs 249.

Brackets 254, 254', 255, and 255' are fixed to the axle housings by bolt assemblies 259 and brackets 260, 261, 262 and 263 respectively on the top of the axle housings 244, one above each bracket. Brackets 259 and 262, which are mounted on housing extensions 246 at the left side of both axles 220 and 222 have upper torque rod mounting arms 264 which extend upwardly from the inner side of brackets 260 and 262. Torque rod mount-

ing arms 264 are longer in this embodiment than in the preferred embodiment of FIGURES 2-5 to give a longer torque radius arm since only two upper torque rods 266 are used instead of four as in the embodiment of FIGURES 2-5. The bracket 263 (FIGURE 6) on housing extension 248 of axle 222 over bracket 255' is merely a bolt clamp plate over the top of the axle for mounting the bracket 255' under the axle.

Bracket 261 on housing extension 248 of axle 220, in addition to being a bolt clamp plate over the top of the axle for mounting the bracket 254' under the axle, has a boss 272 for rigidly mounting a ball pin assembly 274. Ball pin assembly 274 forms part of a universal joint connection 278 to one end of sway bar 280 which extends diagonally across the assembly 218. The other end of sway bar 280 is provided with a universal joint connection 282 to the trunnion bracket assembly 284 fixed to frame 12 at the left side of the tandem axle assembly 218. Universal joint connection 282 is provided by a ball pin assembly fixed in an opening in boss 283 on the front of left trunnion bracket assembly 284. Sway bar 280 provides lateral stabilization for front axle 220 and locates axle 220 in transverse relation to frame 12 regardless of unit articulation. Rear axle 222 is held in lateral alignment by leaf spring assemblies 249.

Upper torque rods 266 are provided at the left side and lower torque rods 266a are provided at both sides of assembly 218. Upper torque rods 266 are universally connected to frame bracket 284 at their ends adjacent the center of assembly 218 by rubber bushed ball pin assemblies 289 structurally identical with those used in the first embodiment and at their other ends are similarly universally connected to axle mounted upper torque rod mounting arms 264. Lower torque rods 266a are similarly universally connected at their adjacent ends to the lower portions of trunnion bracket assemblies 284 and at the other ends to torque rod mounting arms 256 of brackets 254 and 255 and 254' and 255' at the left and right sides respectively of assembly 218 by rubber bushed ball pin assemblies 289.

Axes 220 and 222 each contain a conventional gear differential 290 (FIGURE 8), which is journalled on carriers 240, driven by spur gear reduction from the bevel gear inputs and are drive connected to oppositely extending axle shafts 292 extending through housings 246 and 248. At their outer ends shafts 292 are coaxially fixed to the input of torque transmitting uniform velocity universal joints 296. The output of each universal joint 296 is integral with a live spindle 298 which is connected for unitary rotation with the associated wheel as will be explained presently.

The shank 300 of a housing and steering knuckle mount element 302 is butt welded at 304 to each end of the housings of axles 220 and 222. Bowl 306 of each element 302 partially encloses the associated universal joint 296. An upwardly projecting member 308 which is fixed to the top of bowl 306 provides a king pin like shank 310 which pivotally supports upper steering knuckle boss 312. A downwardly projecting member 314 which is fixed to the bottom of bowl 306 provides a king pin like shank 316 which is coaxial with shank 310 and pivotally supports lower steering knuckle boss 318. Upper boss 312 and lower boss 318 are rigidly fixed to cup like steering knuckle 320. Steering knuckle 320, flange 322 of hollow fixed spindle 324 and brake backing plate 326 for internally expandible brake assembly 327 are rigidly connected together by stud and nut assemblies 328 and pivot as a unit about the common axis of shanks 310 and 316. Wheel hub 330, which is rotatably mounted on spindle 324 by opposed tapered roller thrust bearings 332 and 334, is connected for unitary rotation with live spindle 298 through hub member 336 which is bolted to the outer end of spindle 298. Wheel member 340 and brake drum assembly 342 are coaxially fastened to opposite sides of the radial flange

of wheel hub 330 by stud and nut assemblies 346, drum 342 being disposed in coaxial surrounding operative relation to the brake mechanism 327.

Bearing bushings 348, having radial flanges 350, are fixed in opposed relation in aligned apertures through steering knuckle bosses 312 and 318 for a journal fit with shanks 310 and 316. On the left ends of axles 220 and 222, upper bushings 348 are attached to knuckles 320 with upper steering arms 352 and 354 by bolts 355. Upper bushings 348 on the right hand side of axles 220 and 222 and all four lower bushings are attached with clamp plates 356 to knuckles 320 by bolts 357. Lower steering arms 358 (FIGURE 6) at the opposite ends of front axle 220 are integral with front axle steering knuckles 320, project forwardly and are universally connected at 360 to the opposite ends of front cross tube 362 disposed in front of axle 220. Lower steering arms 364 of rear axle 222 are integral with rear axle steering knuckles 320, project backwardly and are universally connected at 365 to the opposite ends of rear cross tube 366. Rear cross tube 366 is located behind rear axle 222 and front cross tube 362 is located in front of axle 220 to prevent cross tube interference with leaf spring assemblies 249 and with sway bar 280.

Upper steering arms 352 and 354 at the left side of tandem axle assembly 218 are connected to a drag link rod and steering pitman arm construction substantially identical with that illustrated and described in the embodiment of FIGURES 2-5. Referring to FIGURES 6 and 7, this steering linkage comprises a pitman arm 370 pivoted at 372 upon a bracket 374 fixed to a left side of frame 12 for pivotal movement about an axis extending transversely of vehicle frame 12, a straight adjustable length drag link 376 universally connected at its opposite ends to upper steering arm 354 and to the exterior side of pitman arm 370, a bent drag link 378 universally connected at its opposite ends to upper steering arm 352 and the interior side of pitman arm 370 and having a portion extending forwardly longitudinally of the frame from its connection with pitman arm 370 to provide clearance for the left front wheel to assure a small vehicle turning radius as in the first embodiment and a main link 380 universally connected to pitman arm 370 at its rear end and extending forwardly of the vehicle and connected to the steering mechanism in the same manner as shown and described in connection with the first embodiment.

FIGURES 9 through 9B disclose a dirigible tandem drive axle assembly 400 constituting a further embodiment of the invention comprising closely spaced front and rear dirigible drive axles 402 and 404 adapted to be supported at their outer ends by ground engaging wheels, a pair of spaced parallel longitudinally extending leaf springs 406 extending between and resting at their opposite ends upon pillow blocks 408 and 410 on the top of the housings of axles 402 and 404 adjacent their outer ends, a transversely extending trunnion tube 412 extending between springs 406 and pivotally suspended from the center thereof in brackets 414 secured to springs 406 by U-bolts 416, and frame support brackets 418 fixed to tube 412 adjacent the inner face of brackets 414 to which the frame 12 is fixed.

Turning of axles 402 and 404 about their own axes in response to the application of driving and braking torques thereto is prevented by parallelogram systems of torque rods extending between frame support brackets 418 and the respective axles 402 and 404. Axle 404 is stabilized at each end by a longitudinally extending upper torque rod 420 universally connected at its opposite ends to the top of the housing of axle 404 and to bracket 418 and at each end by a longitudinally extending lower torque rod 422 universally connected at its opposite ends to the bottom of the housing of axle 404 and to bracket 418 beneath the axis of trunnion tube 412 as is most clearly shown in FIGURE 9B. The universal connections at the opposite ends of the torque rods are preferably of the

form disclosed in United States Patent No. 2,755,097 issued July 17, 1956, to E. V. Elconin for Torque Rod Mounting for Vehicle Suspension. Axle 402 is similarly stabilized by upper and lower torque rods 424 and 426 at its opposite ends.

The wheel mounting flanges 428 and 430 at the opposite ends of axles 402 and 404 respectively are journaled upon hollow spindle axial extensions of the steering knuckles 432 and 434 and universally drive connected to the outer ends of the axle shafts and the steering knuckles 432 and 434 are pivotally mounted upon the outer ends of the axle housings in substantially the same manner as in the embodiment of FIGURES 6 to 8.

The steering knuckles 432 at the opposite ends of axle 402 are interconnected by a cross tube 436 extending rearwardly of axle 402 between and universally connected at its opposite ends to lower steering arms 438 fixed to the lower bosses of the knuckles 432. Steering knuckles 434 at the opposite ends of axle 404 are interconnected by a cross tube assembly 440 extending rearwardly of axle 404 between and universally connected at its opposite ends to lower steering arms 442 fixed to the lower bosses of the knuckles 434.

Steering motion is imparted to steering knuckles 432 and 434 by a linkage comprising a first adjustable length drag link 442 (FIGURE 9A) universally connected at its forward end to a steering wheel controlled pitman arm (not shown) pivoted at 444 relative to frame 12 and universally connected at its rearward end to a lever 446 pivoted on bracket 447 fixed on frame 12 at 448, a second adjustable length drag link 450 (FIGURES 9A and 9) universally connected at its opposite ends to lever 446 and to a depending pitman arm 452 pivotally mounted at 454 upon a bracket 456 fixed to frame 12. The pivot axis of pitman arm 452 is substantially midway between axles 402 and 404 longitudinally of the vehicle frame 12. Pitman arm 452 is connected to an upper steering arm 458 fixed to the upper boss of the left steering knuckle 434 of rear axle 404 by a straight adjustable length drag link 460 having universal connections at its opposite ends to arms 452 and 458 as in the previous embodiments. The brake actuating fluid motor 462 for the left end of axle 404 is mounted upon steering arm 458 as shown. Pitman arm 452 is operatively connected to steering arm 464 fixed to the upper boss of steering knuckle 432 associated with the left end of front axle 402 by a bent drag link 466 having substantially the same configuration as the corresponding drag links in the previous embodiments, universal connections to arms 452 and 464 being provided at its opposite ends of the type disclosed in the previous embodiments. Lateral stabilization of axle 402 relative to frame 12 is effected by a sway bar universally connected to the frame 12 through bracket 447 at 468 (FIGURE 9A) and to a bracket (not shown) fixed to front axle 402. Rear axle 404 is laterally stabilized through the action of springs 406 as in the previous embodiment.

FIGURES 10 and 11 disclose a dirigible tandem drive axle assembly 500 constituting a fourth embodiment of the present invention and embodying closely spaced dirigible drive axles 502 and 504. The suspension comprising leaf springs 506, trunnion tube 508, spring attachment bracket 510 pivoted to tube 508 and fixed by U-bolts 511 to the center of springs 506, and frame support brackets 512, and the parallelogram system of torque rods comprising upper torque rods 514 and lower torque rods 516 are substantially identical with the structure of the embodiment of FIGURES 9 to 9B. Likewise, the steering linkage comprising main drag link 518, pitman arm 520 pivoted on bracket 522 fixed to frame 12, rearwardly extending straight drag link 524 and forwardly extending bent drag link 526 is substantially identical with the steering linkage of the embodiment of FIGURES 9 to 9B. The arrangement of steering knuckles 528 and 530, the upper steering arms 532 and 534, the lower

steering arms 536 and 538 and of cross tubes 540 and 542 is substantially identical with the corresponding components of the embodiment of FIGURES 6 to 8.

The embodiment of FIGURES 10 and 11 differs primarily from the previous embodiments in that it embodies a transverse axle stabilizing mechanism 544 associated with each axle 502 and 504 of the general form disclosed in association with a non-dirigible tandem drive axle assembly in United States Patent No. 2,750,200 issued June 12, 1956 to W. F. Scheel for Tandem Axle Suspension. The transverse axle stabilizing mechanisms 544 are located intermediate axles 502 and 504 and each comprise an equalizer arm 546 pivotally mounted at its center about an axis normal to the axle axis upon a yoke-like bracket 548 fixed to the housing of the associated axle, and a pair of oppositely extending guide rods 550 and 552 each extending transversely of the vehicle frame 12 and universally connected at its opposite ends to equalizer arm 546 and one of the frame support brackets 512 as shown.

Mechanisms 544 prevent movement of axles 502 and 504 laterally of frame 12 without inhibiting tipping of the axles or displacement of the axles toward or from frame 12 to conform to ground irregularities.

The dirigible tandem drive axle assembly 600 shown in FIGURES 12, 13 and 14, constitutes a fifth embodiment of the present invention. Tandem axle assembly 600 comprises a pair of closely spaced parallel front and rear dirigible drive axles 602 and 604, adapted to be disposed beneath the front end of the frame 12 of the vehicle 10 and suspend frame 12 thereon through a suspension comprising spaced parallel longitudinally extending leaf springs 606 and 608 extending between axles 602 and 604 adjacent their outer end, a spring attachment bracket 610 fixed to the center of each of the leaf springs 606 and 608 by U-bolts 612, a trunnion tube 614 extending between and journaled at its opposite ends in spring attachment brackets 610, and frame support brackets 616 and 618 fixed to trunnion tube 614 adjacent the spring attachment brackets at the opposite ends of trunnion 614 and fixed to the frame 12 as is most clearly shown in FIGURE 13.

Turning of the axles 602 and 604 about their axes in response to braking and driving torques applied thereto is prevented by a parallelogram system of torque rods consisting of upper torque rods 620 and 622 extending respectively from the top of the housing of axle 602 to the frame support bracket 616 and from the top of the housing of axle 604 and the frame support bracket 618, universal joint connections of the rubber bushed ball type being provided at the opposite ends of torque 620 and 622 as in the previous embodiments. Beneath the plane defined by the center lines of axles 602 and 604 are longitudinally extending torque rods 624, 626, 628 and 630, torque rods 624 and 626 being similarly universally connected at their opposite ends to axle 602 and to brackets 616 and 618 respectively. Torque rods 628 and 630 are similarly universally connected at their rear end to the underside of the housing of axle 604 and at their forward ends to brackets 616 and 618. The manner of mounting of the torque rods to the frame mounting brackets is illustrated in FIGURE 13.

The outer end construction of axles 602 and 604 is of the general form disclosed in the previous embodiment consisting of a steering knuckle 632 pivoted on the housing of axle 602 and providing a hollow spindle support for the wheel hub, an upper steering arm 634 fixed to steering knuckle 632 and extending inwardly as shown, and a lower steering arm 636 fixed to the underside of steering knuckle 632. The wheels at the opposite ends of axle 602 are interconnected by a cross tube 638 extending in front of axle 602 and universally connected at its opposite ends to the forwardly extending lower steering arms 636. The wheels at the opposite ends of rear axle 604 are similarly interconnected by a cross tube

640 extending rearwardly of axle 604 and universally connected at its opposite ends to the lower steering arms 636.

The steering mechanism connected to upper steering arms 634 of axles 602 and 604 at the left side of the vehicle comprises a main forwardly extending drag link 642 which is operatively connected to the vehicle steering wheel in the manner disclosed and described in connection with the previous embodiments and universally connected to a depending pitman arm 644 pivotally mounted about a transversely extending axis upon a bracket 646 fixed to the exterior of the left side of frame 12 as shown in FIGURE 12. Upper steering arm 634 of axle 604 is operatively connected to pitman arm 644 by a rearwardly extending straight drag link 648 which is universally connected at its opposite ends to pitman arm 644 and to upper steering arm 634 of axle 604. The upper steering arm 634 of axle 602 is operatively connected to pitman arm 644 by a drag link 650 which is universally connected at its rear end to the inner side of pitman arms 644, extends forwardly from that connection beneath spring 604 and is bent outwardly substantially mid-way of its length and extends forwardly to its universal connection with upper steering arm 634 of axle 602. As in the previous embodiments this bent construction of the forwardly extending drag link permits turning of the front left wheel to the maximum extent possible with the suspension provided without interference from the steering mechanism.

The embodiment of the invention shown in FIGURES 12 through 14 differs primarily from the previous embodiments in that each of the axles 602 and 604 is equipped with a lateral stabilizing mechanism disposed above the axle and comprising an equalizer arm 652 pivotally mounted about a vertical axis upon a stud 654, a pair of guide rods 656 and 658 extending oppositely toward the right and left side of the frames respectively and universally connected at their opposite ends by rubber bushed ball joints to equalizer arm 652 and brackets 660 and 662 respectively, which are fixed to the upstanding end wall of the channels of frame 12 as shown in FIGURE 12. This lateral stabilizing mechanism permits free axial displacement of the axles 602 and 604 relative to the frame 12 and free-tipping movement of axles 602 and 604 relative thereto while preventing any relative lateral movement therebetween.

From the foregoing it is apparent that there are hereby provided new and improved vehicle front tandem axle assemblies with tandem steering axles. The invention provides in a front tandem axle assembly with steering axles a spring suspension with leaf springs trunnion tube mounted at the mid-points to the vehicle frame and which carries the load equally on both front axles. It provides for steering of tandem wheels at one side of a front tandem axle assembly to be proportioned by a pivotally mounted pitman arm and/or different steering arm lengths in such a manner that the tandem wheels turn about a common center. It provides cross tube linkage for each steering axle which insures that, for any particular instant during a turn, wheels at opposite axle ends turn about substantially the same center. It provides front tandem axle assemblies which have parallelogram systems of torque rods. It provides front tandem axle assembly spring end axle hangers which suspend spring end pillow blocks beneath the axles. It also provides an elliptical inverted leaf spring with spring ends slidably resting on pillow blocks suspended beneath front tandem axles.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range

of equivalency of the claims are therefore intended to be embraced therein.

What is to be claimed and desired to be secured by United States Letters Patent is:

- 5 1. In a vehicle, a tandem axle assembly adapted to be disposed beneath the forward end of a vehicle frame, closely spaced parallel front and rear axles, wheel mounting assemblies pivotally mounted for steering movement at each end of said front and rear axles, a trunnion tube, a pair of frame support brackets adapted to be fixed to the vehicle frame at its opposite sides and fixed to said trunnion tube to fix said trunnion tube in transverse relation to said vehicle frame, a spring seat mounted on each end of said tube for pivotal motion about the axis of said trunnion tube, leaf spring assemblies, one of said leaf spring assemblies being centrally mounted in each said spring seat outwardly from the vehicle frame and parallel to the longitudinal axis of said tandem axle assembly, one end of each said leaf spring assembly resting on each of said front and rear axles, oppositely longitudinally extending upper torque rods connected at their remote ends to said front and rear axles by universal joint connections above the longitudinal axis of each respective axle and connected at their adjacent ends by universal joint connections to said frame support brackets, lower torque rods in parallel relation to said upper torque rods connected at their remote ends to said front and rear axles by universal joint connections below the longitudinal axis of each respective axle and connected at their adjacent ends by universal joint connections to said frame support brackets, an upper steering arm fixed to one of the pivoted wheel mounting assemblies of each of said axles on the same side of said assembly, a pitman arm pivotally mounted in fixed relation to said frame mounting bracket substantially centrally with respect to the axle spacing of said tandem axle assembly, a forward adjustable length drag link rod connected at its opposite ends by universal joint assemblies to the upper steering arm of said front axle and to said pitman arm in predetermined spaced relation to the pivot axis of said pitman arm, a rear adjustable length drag link rod connected at one end by a universal joint assembly to the upper steering arm of said rear axle and at the other end by a universal joint assembly to said pitman arm at a point located between said universal joint connection of said forward drag link rod and the pivotal axis of said pitman arm and nearer to the universal joint connection of said forward drag link rod, a main steering drag link movable under operator control connected by a universal joint assembly to said pitman arm at a point located between the pivotal axis of said pitman arm and the universal connection to said rear drag link rod and nearer to said rear drag link rod, a lower steering arm on each said pivoted wheel mounting assembly, and a cross tube associated with each axle and connected by universal joint assemblies to the lower steering arms thereof.
- 10 2. In the tandem axle assembly defined in claim 1, rigid sway bar member having a universal joint adapted for connection with the vehicle frame at one end and a universal joint connection with an axle of said tandem axle assembly at the other end, said sway bar member extending, when in operative position, generally transversely of said frame.
- 15 3. In the tandem axle assembly defined in claim 1, lateral stabilization means for connection to said vehicle frame and connected to each axle of said tandem axle assembly comprising an equalizer arm pivotally mounted at its mid-point to each axle, a pair of oppositely laterally extending rods each connected by universal joints at one end to one end of said equalizer arm and adapted at the other end for universal connection to one side of the vehicle frame.
- 20 4. In a dirigible tandem axle assembly, a pair of closely spaced parallel dirigible axles having wheel hub mount-

ing members pivoted at their outer ends, a centrally pivoted suspension mechanism interconnecting said axles and adapted to support a portion of the frame of a vehicle, and a steering linkage operative to impart simultaneous pivotal steering movements to the wheel mounting members at the outer ends of each of said axles, said linkage comprising a pitman arm pivoted intermediate said axles about a laterally extending axis fixed relative to said frame, means comprising rearwardly and forwardly extending drag links pivoted respectively to said pitman arm and fixed steering arms on said wheel hub mounting members so as to provide lever systems of different effective length interconnecting said pitman arm and the wheel hub mounting members of said axles at one side of said vehicle, the lever system connected to the forward wheel hub mounting member being shorter than that connected to the rearward wheel hub mounting member, and means interconnecting the wheel hub mounting members of each axle for simultaneous movement, the forwardly extending drag link being connected to said pitman arm a point further distant from the pitman arm pivot than the connection between the pitman arm and the rear drag link, and a main link extending from the steering control for the assembly pivoted to the pitman arm between the pivot axis of the pitman arm and its connection to the rearward drag link.

5. In a vehicle, a tandem axle assembly comprising two closely spaced axles supported at opposite ends by dirigible ground engaging wheels, a chassis, a suspension system comprising at each side of the vehicle a longitudinally extending spring member pivoted upon the chassis and freely slidably pivotally connected to said axles axially inwardly of said wheels, a system of brake torque transfer rods interconnecting said axles and said chassis, and vehicle steering mechanism operatively connected to all of said dirigible wheels comprising a lever pivoted upon the chassis intermediate said axles, oppositely extending rods universally connected to said lever and operably connected to the dirigible wheels of the respective axles and means for actuating said lever comprising a main reciprocable link pivotally connected to said lever at a point intermediate its frame pivot and its connection to said rods.

6. In a vehicle, a vehicle frame and a dirigible tandem axle assembly adapted to be disposed beneath the forward end of said vehicle frame for pivotally supporting said frame, said tandem axle assembly comprising closely spaced parallel front and rear axles, wheel mounting assemblies pivotally mounted for steering movement at each end of said front and rear axles, an upper steering arm fixed to one of the pivoted wheel mounting assemblies of each of said axles on the same side of said tandem axle assembly, a pitman arm pivotally mounted in fixed relation to said frame substantially centrally with respect to the axle spacing of said tandem axle assembly and at a predetermined distance inwardly with respect to the pivotal axes of said wheel assemblies carrying said upper steering arms, a forward adjustable length drag link rod connected at its opposite ends by universal joint connection assemblies to the upper steering arm of said front axle and to said pitman arm in predetermined spaced relation to the pivotal axis thereof, a rear adjustable length drag link rod universally connected at one end to the upper steering arm of said rear axle and universally connected at the other end to said pitman arm at a point located between the pivotal axis of said pitman arm and the universal connection to said forward drag link rod and closer to said universal connection to said forward drag link rod than to the pivotal axis of said pitman arm, a main steering drag link movable under operator control and connected by a universal joint assembly to said pitman arm at a point between the pivotal axis of said pitman arm and the universal connection to said rear drag link rod and closer to the universal connection to said rear drag link rod than to the pivotal axis of said pitman arm,

a lower steering arm on each of said pivoted wheel mounting assemblies, and a cross tube associated with each axle and connected by universal joint assemblies to the lower steering arms thereof.

7. In a vehicle, a vehicle frame, and a dirigible tandem axle assembly adapted to be disposed beneath the forward end of a vehicle frame, closely spaced parallel front and rear axles for pivotally supporting said frame, said tandem axle assembly comprising wheel mounting assemblies pivotally mounted for steering movement at each end of said front and rear axles, an upper steering arm fixed to one of the pivoted wheel mounting assemblies of each of said axles on the same side of said tandem axle assembly, said steering arms extending forwardly from said wheel mounting assemblies and having integral curved steering arm portions extending inwardly and rearwardly from associated ones of said wheel mounting assemblies, said steering arm for the forward axle of the assembly being shorter than the steering arm for the rearward axle of the assembly with the end of said curved steering arm portion for said forward axle being appreciably closer to the longitudinal axis of its associated axle than the end of said curved steering arm portion for said rearward axle is to the longitudinal axis of its associated axle, a pitman arm pivotally mounted in fixed relation on said frame substantially centrally with respect to the axle spacing of said tandem axle assembly and at a predetermined distance inwardly with respect to each of said steering arms, a forward adjustable length drag link rod connected at its opposite ends by universal joint connection assemblies to the upper steering arm of said front axle and to said pitman arm in predetermined spaced relation to the pivotal axis of said pitman arm, a rear adjustable length drag link rod connected at one end by a universal joint assembly to the upper steering arm of said rear axle and at the other end to said pitman arm by a universal joint assembly at a point located between said universal joint connection of said forward drag link rod and the pivotal axis of said pitman arm, a main steering drag link movable under operator control connected by a universal joint assembly to said pitman arm at a point located between the pitman arm pivot and the universal connection to said rear drag link rod, a lower steering arm on each of said pivoted wheel mounting assemblies, and a cross tube associated with each axle and connected by universal joint assemblies through the lower steering arms thereof.

8. In the tandem axle assembly as defined in claim 7, a rigid sway bar member having a universal joint adapted for connection with said frame at one end and a universal joint connection with one of said axles at the other end, said sway bar member extending, when in operative position, across from one side of the frame to the other.

9. In a dirigible tandem front axle assembly, front and rear closely spaced parallel dirigible axles having wheel hub mounting members pivoted at their outer ends, a centrally pivoted suspension mechanism interconnecting said axles and adapted to support the forward portion of the frame of the vehicle, and a steering linkage operative to impart simultaneous pivotal steering movements to the wheel mounting members at the outer ends of each of said axles, said linkage comprising a pitman arm pivoted intermediate said axles about a laterally extending axis fixed relative to said frame, means comprising rearwardly and forwardly extending drag links pivoted respectively to said pitman arm and to steering arms rigid with said wheel hub mounting members so as to provide lever systems of different effective length interconnecting said pitman arm and the wheel hub mounting members of said axles at one side of said vehicle, the lever systems being effective to impart a greater turning movement to the wheel hub mounting members of the front axle for a given increment of movement of said pitman arm, and means interconnecting the wheel hub mounting members of each axle for simultaneous movement,

the forwardly extending drag link being connected to said pitman arm at a point more distant from the pitman arm pivot than the connection between the pitman arm and the rear drag link and a main link extending from the steering control for the assembly pivoted to the pitman arm between the pivot axis of said pitman arm and its connection to the rearward drag link.

10. In a vehicle a tandem front axle assembly comprising closely spaced front and rear axles supported at opposite ends by dirigible ground engaging wheels, a chassis, a suspension system comprising at each side of the vehicle a longitudinally extending spring member pivoted upon the chassis and freely, slidably, pivotally connected to said axles axially inwardly of said wheels, a system of brake torque transfer rods interconnecting said axles and said chassis, and vehicle steering mechanism operatively connected to all of said dirigible wheels comprising a lever pivoted upon the chassis intermediate said axles, oppositely extending rods universally connected to said lever and operably connected to the dirigible wheels of the respective axles, means for actuating said lever comprising a main reciprocable link pivotally connected to said lever at a point intermediate its frame pivot and its connection to said rods, the connection between said rods and said lever and between said rods and said dirigible wheels being so arranged as to impart a greater turning movement to the wheels at the opposite ends of the front axle than the wheels at the opposite ends of the rear axle upon a given movement of said lever.

11. In a vehicle, a vehicle frame, and a dirigible tandem axle assembly adapted to be disposed beneath the forward end of a vehicle frame, closely spaced parallel front and rear axles for pivotally supporting said frame, said tandem axle assembly comprising wheel mounting assemblies pivotally mounted for steering movement at each end of said front and rear axles, an upper steering arm fixed to one of the pivoted wheel mounting assemblies of each of said axles on the same side of said tandem axle assembly, said steering arms extending forwardly from said wheel mounting assemblies and having integral curved steering arm portions extending inwardly and rearwardly from associated ones of said wheel mounting assemblies, said steering arm for the forward axle of the assembly being shorter than the steering arm for the rearward axle of the assembly with the end of said curved steering arm portion for said forward axle being appreciably closer to the pivotal axis of its asso-

ciated wheel mounting assembly than the end of said curved steering arm portion for said rearward axle is to the pivotal axis of its associated wheel mounting assembly, a pitman arm pivotally mounted in fixed relation on said frame substantially centrally with respect to the axle spacing of said tandem axle assembly and at a predetermined distance inwardly with respect to each of said steering arms, a forward adjustable length drag link rod connected at its opposite ends by universal joint connection assemblies to the upper steering arm of said front axle and to said pitman arm in predetermined spaced relation to the pivotal axis of said pitman arm, a rear adjustable length drag link rod connected at one end by a universal joint assembly to the upper steering arm of said rear axle and at the other end to said pitman arm by a universal joint assembly at a point located between said universal joint connection of said forward drag link rod and the pivotal axis of said pitman arm, a main steering drag link movable under operator control connected by a universal joint assembly to said pitman arm at a point located between the pitman arm pivot and the universal connection to said rear drag link rod, a lower steering arm on each of said pivoted wheel mounting assemblies, and a cross tube associated with each axle and connected by universal joint assemblies through the lower steering arms thereof.
